UNITED STATES PATENT OFFICE

137,448

DESIGN FOR A REFUSE RECEPTACLE

Arthur Deutsch, Chicago, Ill.

Application November 1, 1943, Serial No. 111,562

Term of patent 14 years

To all whom it may concern:

Be it known that I, Arthur Deutsch, a citizen of Austria, having received first citizenship papers of the United States, residing at Chicago, in the county of Cook and State of Illinois, have invented a new, original, and ornamental Design for a Refuse Receptacle, of which the following is a specification, reference being had to the accompanying drawing, forming a part thereof.

Fig. 1 is a side elevational view of a refuse receptacle embodying my new design.

Figs. 2 and 3 are, respectively, front and rear elevational views of the same.

Fig. 4 is a plan view of the same.

Fig. 5 is a side elevational view of the same with the cover open.

I claim:

The ornamental design for a refuse receptacle, substantially as shown.
